UNITED STATES PATENT OFFICE

AKIM LITWIN, JACOB A. LITWIN, AND MAX LITWIN, OF CINCINNATI, AND BORIS LITWIN, OF ST. BERNARD, OHIO

DESIGN FOR A RING

Application filed October 14, 1930. Serial No. 37,258. Term of patent 3½ years.

To all whom it may concern:

Be it known that we, AKIM LITWIN, JACOB A. LITWIN, and MAX LITWIN, citizens of the United States of America, and residents of Cincinnati, county of Hamilton, and State of Ohio, and BORIS LITWIN, a citizen of the United States of America, and a resident of St. Bernard, county of Hamilton, and State of Ohio, have invented a new, original, and ornamental Design for a Ring of which the following is a specification, reference being made to the accompanying drawing, forming a part thereof.

Fig. 1 is a perspective view of a ring, showing our design.

Fig. 2 is a bottom plan view of the ring shown in our design. The opposed side perspective view of the ring is the same as that illustrated in Fig. 1.

We claim:

The ornamental design for a ring as shown and described.
